THROTTLE CONTROL LINKAGE ADJUSTMENT

Richard W. Buell, Webster A. Lobdell, and Gordon W. Wrinn, Detroit, Mich., assignors to Claude Sintz, Inc., Detroit, Mich., a corporation of Michigan

Application March 12, 1956, Serial No. 570,732

7 Claims. (Cl. 74—586)

This invention relates to a fuel control system and refers more particularly to a throttle control linkage adjustment therefor.

The flow of fuel-air mixture in a carburetor is ordinarily controlled by a manually operated throttle or accelerator member which is connected to the operating lever or control arm of the carburetor by suitable linkage. However, in the production and assembly of motor vehicles, it is not possible to locate the carburetor in precisely the same position on every vehicle and, hence, the distance between the carburetor and the throttle or accelerator member varies.

With the foregoing in mind, one object of this invention is to provide linkage for connecting the throttle or accelerator member to the operating lever or control arm of the carburetor which is adjustable to compensate for minor differences in the distance between the carburetor and the accelerator member.

Another object of this invention is to provide linkage as described above, which is composed of a relatively few simple parts and yet which is highly effective in the performance of its intended function.

Other objects of the invention will become apparent as the following description proceeds especially when considered in conjunction with the accompanying drawing, wherein:

Figure 1 is a side elevation view of a fuel control system including the adjustable linkage embodying the features of the present invention.

Figure 2 is a top plan view of the linkage shown in Figure 1.

Figure 3 is a sectional view taken along the line 3—3 on Figure 1.

Figure 4 is a fragmentary side elevation of a modification.

Figure 5 is an end elevation of a part of Figure 4.

Figure 6 is a fragmentary side elevation of another modification.

Referring now more particularly to the drawing, a carburetor is indicated generally at 10 having an operating lever or control arm 12 which is movable to the right and to the left as viewed in Figure 1 to vary the flow of fuel-air mixture in the carburetor. The accelerator pedal or throttle member 14 is in the form of an elongated foot operated pedal which is pivotally supported on the floor 16 of a motor vehicle, the pivotal connection being indicated at 18. A link 20 has one end pivotally connected to an ear 22 carried by the pedal 14 and the other end of the link 20 is secured to an end of the linkage 24. The opposite end of the linkage 24 is connected to the control member 12.

Referring now in detail to the linkage 24, such linkage comprises the elongated elements or rods 26 and 27. The rod 26 has an outer portion 28 of uniform circular cross section and has an inner portion 30 which is flattened to the narrow configuration illustrated. The outer end of portion 28 has a socket 32 which extends into the

side thereof. This socket has a hemispherical bottom which merges into a cylindrical portion which extends to the outer surface of portion 28. A threaded shank 34 has its upper end threaded into the tapped recess in the under side of the operating lever 12 and has a ball 36 at the lower end which is disposed in the socket 32 and which has a radius approximately equal to the radius of curvature of the hemispherical bottom surface of the socket. The radius of the cylindrical portion of the socket 10 is the same as the hemispherical bottom surface so that the ball may be freely inserted into the socket and readily removed therefrom. When retained in the socket, the ball has a limited universal movement.

In order to retain the ball in the socket, a flexible resilient U-shaped sheet metal retaining sleeve or member 38 embraces the outer end of the rod 26. The free ends of the retaining member 38 are flared slightly as indicated at 40 and the flared portions bulge outwardly in the region of the socket. The bulged portions of the flared ends partially overlap the socket to retain the ball therein and to enable the ball to be inserted into and removed from the socket with a force sufficient to expand the retainer member. It will be noted that the shank 34 has an intermediate enlarged portion of polygonal cross section indicated at 42. By the application of a suitable wrench, the shank may be rotated to thread its upper end into or out of the control lever 12 without removing the ball from the socket.

The inner end portion 30 of rod 26 has a slot 44 therein which is elongated in the direction of length of the rod. The inner end portion 30 is bent at a substantial angle along a line intermediate the ends of the slot and extending across the slot.

The other element or rod 27 is of uniform circular cross section throughout its length and has a diameter less than the width of the slot to enable it to be inserted in the slot. The intermediate portion 46 of rod 27 extends into the slot in the region inwardly beyond the bend, and the inner extremity 48 of rod 28 is turned downwardly at right angles to the intermediate portion 46 and extends through the slot at a point outwardly beyond the bend. Washers 49 are loosely sleeved over the extremity 48 of rod 28 on opposite sides of the slotted inner end portion 30 and a nut 50 is threaded on the end of the extremity. The intermediate portion 46 bears against the inner end of slot 44.

The outer end extremity 52 of rod 27 is bent upwardly at right angles to the intermediate portion 46 and in the plane of the inner extremity 48. The outer end extremity 52 is connected to the link 20 in any suitable manner.

It will be evident from the foregoing that the length of the linkage 24 may be readily varied by merely loosening the nut 50 to permit the extremity 48 to slide longitudinally in the portion of the slot outwardly of the bend. When the selected position of adjustment has been obtained, the nut 50 is tightened to press the washers 49 tightly together on opposite sides of the slotted portion 30. The intermediate portion 46 of the rod, of course, provides an abutment for the opposite side of the upper washer.

In accordance with this construction, the linkage is rigid in any position of adjustment, that is, any tendency for the rods 26 and 27 to turn or pivot relative to each other is opposed.

Figures 4 and 5 show a modification. The construction of Figures 4 and 5 differ from that previously described in that the opposite sides of rod 27 are staked to provide the angularly spaced laterally outwardly projecting integral parts or tabs 60 adapted to overlie and provide an abutment for the upper washer 49. A lock

washer 61 may be provided, and may also be used in the construction of Figures 1-3 if desired.

The construction of Figure 6 differs from Figures 1-3 in that the rod is upset to provide an integral annular disc-like part 62 adapted to overlie and provide an abutment for replacing the upper washer 49. Again, a lock washer 61 may be employed.

The rod 26 in both the forms of Figures 4-6 has a slot 44 similar to slot 44 but closed at the bend as indicated at 65. The bent inner end is formed of furcations 66 which define a slot 67 therebetween open at the inner end. The slot 67 closely receives the rod 27. Otherwise rod 26 is exactly like rod 26. The slot 44 extends outwardly the same distance and has the same width as slot 44 and closely receives the bent inner end of rod 27. The part 62 has a diameter greater than the width of slot 44 so as to extend beyond the slot at opposite sides thereof.

The slot 67 is open at the inner end to permit assembly of rod 27 with rod 26 when rod 27 is staked or upset as in Figures 4-6. The web 65 provides reinforcement.

What we claim as our invention is:

1. Adjustable linkage for interconnecting two members including first and second elongated elements having their outer ends respectively adapted for connection to the members, the inner end portion of one of said elements having a slot therein elongated in the direction of length of said one element and closed at both ends, said inner end portion of said one element being bent at a substantial angle along a line intermediate the ends of said slot and extending across said slot, said other element extending through said slot in one direction inwardly of the bend and having a laterally turned inner extremity extending through said slot in the opposite direction outwardly of the bend, and clamping means carried by said extremity of said other element for clamping the latter to said inner end portion of said one element in the slot thereof in selected positions of adjustment to vary the length of said linkage.

2. Structure as defined in claim 1 in which said clamping means comprises a nut threaded on said extremity at one side of said slot and an abutment on said extremity at the other side of said slot cooperable with said nut to clamp said slotted portion of said one element therebetween.

3. Structure as defined in claim 2 in which the inner end of said slot provides a bearing surface for said other element.

4. Structure as defined in claim 1 in which said clamping means comprises a nut threaded on said extremity at one side of said slot, and an abutment on said extremity at the other side of said slot cooperable with said nut to clamp said slotted portion of said one element therebetween, said abutment comprising a washer directly abutting said other element outwardly of its extremity.

5. Structure as defined in claim 1 in which said clamping means comprises a nut threaded on said extremity at one side of said slot, and an abutment on said extremity at the other side of said slot cooperable with said nut to clamp said slotted portion of said one element therebetween, said abutment including angularly spaced integral tabs projecting laterally outwardly from opposite sides of said extremity.

6. Structure as defined in claim 1 in which said clamping means comprises a nut threaded on said extremity at one side of said slot, and an abutment on said extremity at the other side of said slot cooperable with said nut to clamp said slotted portion of said one element therebetween, said abutment including an integral annular disc-like part projecting laterally outwardly from said extremity.

7. Adjustable linkage for interconnecting two members including first and second elongated elements having outer ends respectively adapted for connection to the members, the inner end portion of one of said elements having a slot therein elongated in the direction of length of said one element, said inner end portion of said one element being bent at a substantial angle along a line intermediate the ends of said slot and extending across said slot, said other element extending through said slot in one direction inwardly of the bend and having a laterally turned inner extremity extending through said slot in the opposite direction outwardly of the bend, and means for clamping said elements in selected positions of longitudinal adjustment to vary the length of said linkage.
